NEWTON B. CONVERSE, OF FRESNO, CALIFORNIA, ASSIGNOR TO HIMSELF AS TRUSTEE.

BALANCING DEVICE FOR FLYING-MACHINES AND THE LIKE.

1,246,235.

Specification of Letters Patent. Patented Nov. 13, 1917.

Application filed April 27, 1911, Serial No. 623,606. Renewed March 30, 1917. Serial No. 158,732.

To all whom it may concern:

Be it known that I, NEWTON B. CONVERSE, a citizen of the United States, residing at Fresno, in the county of Fresno and State of California, have invented new and useful Improvements in Balanceing Devices for Flying-Machines and the like, of which the following is a specification.

The present invention relates to improvements in flying machines, and the object of the invention is to provide means for automatically balancing the machine at right angles to the lines of force, whether of gravity alone or the resultant of gravity and centrifugal force as when changing the direction of the machine. A further object of the invention is to provide means for balancing the flying machine, which does not have any effect in changing the direction of said machine.

In the accompanying drawings, Figure 1 is a broken perspective view of my improved flying machine, certain parts being omitted; Fig. 2 is a sectional detail view of an electrical connection; Fig. 3 is a plan view of the electro-magnetic mechanism and the shafts operated thereby; Fig. 4 is a broken end view of the same, certain parts being shown in vertical section; Fig. 5 is a plan view of the wind motors; Fig. 6 is a broken end view of the same; Fig. 7 is a diagrammatic view of the electrical connections; Fig. 8 is an enlarged vertical section on the line 8—8 of Fig. 3; Fig. 9 is a broken side view of the parts shown in Fig. 8; Fig. 10 is an enlarged vertical section on the line 10—10 of Fig. 4; Fig. 11 is a plan view of a portion of Fig. 8; Fig. 12 is a longitudinal section of the electro-magnetic mechanism; Fig. 13 is a cross section on the line 13—13 of Fig. 12.

Referring to Fig. 1 of the drawing, 1 indicates the frame of a flying machine, which, for the purpose of illustration, is here shown of the biplane type, although my invention is by no means limited thereto. It has upper and lower planes 2, 3, a front elevator 4, a rear tail piece 5, and a rear direction rudder 6. The mechanism for propelling the machine is omitted, as being of the common and well known construction, and not a part of the present invention, which relates only to the means for maintaining stability.

At a convenient location centrally of the machine, is located a frame comprising a

longitudinal bar 10 and front and rear cross bars 11, 12, in the ends of which are mounted longitudinal shafts 13 carrying helical rotary wind motors 14, which, in the motion of the flying machine against the air, are caused to revolve, thus furnishing the necessary power to operate the mechanism hereinafter described. The helices of these wind motors are respectively right and left handed, so that they turn in opposite directions or toward one another. I have herein shown said power as transmitted from said wind motors by means of pulleys 17 and belts 18, although a non-slipping transmission apparatus may be used in place thereof. Said belts, one of which is crossed, pass around pulleys 20 on the shaft 21 of a direct-current generator 22 of low voltage and are separated by a disk 23. Thus an electric current is generated by the rotation of said wind wheels. On the shaft of the generator is mounted a gear wheel 25 which meshes with intermediate gear wheels 26 on stud shafts 27 on a suitable support 28 connected with the generator frame, said intermediate gear wheels meshing with gear wheels 29 secured by arms 30 to the backs of outer casings 31 of electro-magnetic clutches 32. Each casing is provided with a hub 33 and an outer cylindrical wall 34, between which is wound insulated wire 35 forming an electro-magnetic clutch. Said casing is driven tightly on to a hollow shaft 36 which revolves in the same direction as the generator in ball bearings in a cylindrical box 37 suitably supported upon a base plate 38. Within said hollow shaft lead two insulated wires 40, which, in order to connect to the opposite ends of the energizing coil, are passed through holes 41 in the hollow shaft and hub. The other ends of said wires are connected to collector rings 42, insulated from one another as shown at 43, with which collector rings contact spring supported brushes 44 contained in metal sockets 144 supported upon fiber blocks 45 (see Fig. 2) and connected to wires 63 leading from opposite poles of the generator, one of said wires leading through contacts hereinafter described.

The armature 46 of the electromagnet is slidably keyed upon an end of a shaft 47 hereinafter described, and is normally pressed from said electromagnet by a coiled spring 48 within a chamber 49 formed on said armature, one end of said coiled spring

abutting against the wall 50 of said chamber and the other end abutting against a flange 51 formed on an abutment 52 which has a central cylindrical guide piece 53 received within a cylindrical hole 54 formed in the end of said shaft 47. Said abutment is formed on the side opposite to said guide piece with a recess or chamber 55, in the bottom of which is a hard steel disk 56 which is pressed by said spring against a steel ball 57, which is thus in turn pressed against the end of the hollow shaft 36. When the electro-magnet is energized, the attraction is sufficient to overcome the pressure of the spring and draw the armature up to the face of said electro-magnet. It is however desirable to prevent actual contact with said magnet when energized, in order to avoid any danger of the armature being held by residual magnetism, after it has been deenergized, and, therefore, an air gap is always provided, even in the attracted position of said armature, between said armature and said magnet, this being accomplished by means of a ring 59 of fiber or other non-magnetic material, which offers good frictional resistance, one end of said ring abutting against a circular shoulder 60 formed upon said wall 34 of the electro-magnet and the other terminal portion 61 of the ring flaring outwardly in conical form to receive an outwardly flaring conical flange 62 of the armature. A second important reason why an air gap is left between the electro-magnet and the armature in the attracted position of the latter is because friction between the armature and the non-magnetic ring is better than between the armature and the smooth metallic face of the magnet, and in order to insure that rotation is imparted to the armature as quickly as possible after it is attracted.

By this means, as soon as the circuit is closed between each electro-magnet and the generator, rotation is imparted to the armature and to the shaft 47. Said shaft revolves in ball bearings 64 within boxes 65 and carries between said boxes a flanged drum 66. Each drum has a longitudinal opening through which an end of a tape 67 is passed to the inside of the drum and around the shaft 47, being then sewed to the remainder of the tape. It will thus be seen that when said electro-magnet is energized, the shaft 47 rotates to wind up the tape. The mechanism connected with said tape will be hereinafter explained, but it may be here observed that said mechanism is such that when the magnet is deenergized and the armature is released, the tape is unwound from the shaft, and therefore the shaft is rotated in the opposite direction to that of the electro-magnet. Each shaft 47 has secured on its end a worm 68, which

meshes with a worm wheel 69 on a shaft 70 oscillating in suitable bearings, one of said bearings being in a post 71. Therefore by the winding and unwinding of said tape the shaft 70 is given a movement of oscillation the amplitude of which, however, is not more than half a revolution. In bearings 72 extending from said post can slide vertically a slide bar 73. The shaft 70 carries on its end between said post and slide bar a cam 74, which oscillates in contact with two rollers 75 carried by said slide bar.

To said slide bar 73 are secured arms 76 which carry an insulating box 80, in which is clamped a steel contact pin 81, the lower portion of which is reduced in diameter, and is covered with insulating material 82, and the lower end of which is formed with a socket to receive a platinum pin 83. Said pins 81, operated by their respective shafts, extend downward through sleeves 84 and the upper ends of conduits 85, said sleeves being insulated from said conduits, as shown at 86. Said conduits 85 are connected at their lower ends by a curved mercury conduit 87, and above their lower ends by a horizontal oil conduit 88. In the lower tube 87 is contained mercury, the level of which is, in the normal position of the flying machine, in both tubes slightly above the point where the curved lower conduit 87 depends from the upper vertical conduits 85, said lower conduit being of slightly reduced diameter. In the normal position of the flying machine, the lower ends of said pins depend so as to be just out of contact with said mercury. The upper horizontal tube 88, the vertical tubes 85 and a receptacle 89 connected to said horizontal tubes 88 are filled with oil. Said receptacle 89 is provided at the top with a diaphragm 90 apertured, as shown at 91, of any suitable material. It is necessary that the oil should fill the upper tube 88 at least as high as the upper side of said tube, so as to completely fill said tube 88 in any position of the flying machine. This oil should be sufficiently light to permit globules of mercury, which enter the same, to collect and flow back into the lower tube and not be held separate. These mercury globules are condensed from the mercury vapor generated from the voltaic arc produced at the electric contacts. I have found the apparatus to work successfully with kerosene oil. Water 120 with kerosene floating on the top is also desirable, for the reason that it prevents the carbonization of the kerosene by the voltaic arc, and the oil floating on the top of the water prevents the entrance of air 125 into said water, which would have a tendency to oxidize the mercury in the lower tube at the time that an arc was formed.

The ends of the tapes are connected to pulleys 103, and around each pulley passes 130

a cord 104, each end of which is connected to the middle of a cord 103, the ends of the cord 103 being connected to the rear edges of upper and lower ailerons 106, the front edges of which are secured to the frame of the flying machine, one end of each cord 104 being thus connected to an edge of a lower aileron at one side of the flying machine and the other end being connected to an edge of an upper aileron at the other side of the machine. Said cords 104 pass around pulleys 108 so disposed upon the frame of the flying machine, that when the lower aileron, connected to one end, is depressed, the upper aileron, connected to the other end, is simultaneously raised, and conversely.

The mercury in the tube 87 is connected with the negative pole of the generator by a wire 109, while each of the two pins is connected by a wire 110 to the collector ring on the same side, while the other collector ring is connected by a wire 111 to the positive pole.

The operation of the apparatus is as follows:—When the flying machine is traveling in a straight line upon an even keel, the lower ends of the platinum pins 83 are just out of contact with the mercury in the lower tube 87. But should the flying machine from any cause tip to one side, while in a straight ahead flight, then the contact is made on that side between the mercury and the platinum point.

The circuit is then closed through the clutch on the side to which the ship has been tilted downward and energizes said clutch, which immediately sets in motion the shaft and winds up the tape. The winding up of the tape on that side draws in the pulley 103 on that side, which depresses the lower aileron on that side and raises the upper aileron on the opposite side of the flying machine. The effect of these changes in the positions of the ailerons is to produce a reversal of the tilting of the flying machine.

If the construction were such that the closure of the electric circuit on either side changed the position of a single aileron on one side only of the machine, the effect would be that, on account of said aileron offering more resistance than before to the forward motion of the flying machine in passing through the air, the direction of the machine would be changed, by said aileron causing the ship to turn toward the side upon which said aileron was tilted out of its normal position. By providing two ailerons, on opposite sides of the ship, tilted in opposite directions by the closure of a circuit, the tendencies to change the direction of the ship by the two ailerons neutralize one another.

One reason why each tape 67 is connected to the cords 104 which extends to two

ailers by means of a pulley, which affords a movable union therebetween, instead of a fixed connection, is so that said ailerons will always automatically, when in operation, assume a position in which they offer as little resistance as possible to the air through which the flying machine is passing. For, if they extended from the flying machine at an angle such that they would offer such resistance, then, by reason of such resistance, there would also be a pressure upon them by the air, which pressure would move them into a position offering only the resistance of their edges to the air, since the pulleys permit the cord 104 to easily move so that they assume said position. It is therefore important that all the pulleys over which said cords 104 pass should be as frictionless as possible, but a further and more important reason why the movable union is used instead of a fixed connection is to allow the ailerons at opposite sides of the flying machine to assume positions and angles respectively inclined to the line of flight, such that the pressures on opposite sides of the flying machine shall be equal, and therefore the tendency of each side of the flying machine to lag behind on account of said pressure is the same, so that the operation of the ailerons does not affect or change the general direction of the flight.

If the pins were fixed in relation to the tubes, the result would be that if the machine were tilted to either side and the electro-magnet energized, the shaft would continue to rotate and the tape be wound up and the ailerons moved farther and farther out of their normal position, until the pin was again out of contact with the mercury, which would be not until the machine was again restored to an even keel. Therefore, at that time, said ailerons would be at a very considerable angle, tending to shift the machine about its longitudinal axis in the same direction as that for restoring it to an even keel, or in the reverse direction to that last corrected. In other words, the result would be to produce an overbalance or oscillation of the machine, which would be continued through many vibrations thereof and perhaps for an indefinite period. It is in order to avoid this result that I provide means, the worm 68, worm wheel 69, shaft 70, cam 74, and rollers 75, set in motion by the closing of the electrical circuit, to raise each pin from the mercury with which it was in contact. In other words, as the mercury at either end of the lower tube 87 moves in said tube to come into electrical connection with the pin, the pin retreats from the mercury at said end so that the electrical circuit is broken (unless the tilting of the machine is more rapid than the withdrawal of the pin) and said circuit is only closed again if the mercury

fails to descend in the tube; because, as soon as the circuit is broken, the drum ceases to wind up the tape and the air pressure on the aileron causes the tape to be unwound from the drum, and thus causes the pin to descend into contact with the mercury. Thus the machine is restored to a horizontal position by a step by step movement, the aileron arriving at a neutral or normal position at the same time as, or just before, the flying machine comes to an even keel, thus avoiding an overbalance.

By suitably conforming the cam surface of the cam 74 I am enabled to insure that the elevation of the pin above its normal position shall bear always a definite relation to the angle of elevation of the aileron, that relation being the one best adapted to restore the flying machine to an even keel and without any swinging in the opposite direction therefrom.

It will be observed that the curved conduit 87 is formed with a cusp 120 in the center. If there were no friction between the mercury and the walls of the conduit, the mercury would maintain absolutely the same level, notwithstanding the motion of the conduit. But, owing to the friction with said walls, the motion of the conduit imparts motion to a certain degree to the mercury, which would tend to produce oscillation of the mercury in the conduit due to its high specific gravity. This tendency is prevented by the cusp 120, which checks the momentum of one-half of the mercury by impact thereagainst and the other half by resistance offered by the vacuum produced.

The operation of the device when the flying machine is changing its direction is precisely the same as when flying straight ahead, since the tendency of the mercury to move to the outer side due to centrifugal force has the effect of making a contact on said outer side; and thereby raises the outer side of the machine an amount, which is proper for the banking of the air under the main planes to prevent skidding.

It is evident that the above device is adapted to restore a flying machine to a position in which its transverse direction is at right angles to the lines of force acting upon said flying machine, that is, at right angles to the force of gravity only when the flying machine is going straight ahead, and at right angles to the resultant of the forces of gravity and centrifugal force when the flying machine is changing its direction.

I claim:

1. In a flying machine, the combination of means for changing the relative levels of opposite parts of the machine, electro-magnetic means for controlling said changing means, a contact pin, a vessel containing a conducting fluid with which said pin can

be brought into contact by a difference in 65 level of opposite parts of the ship, and means, actuated in unison with said changing means, for withdrawing said pin out of contact with said liquid, substantially as described.

2. In a flying machine, means for correcting the level of the machine, an element, as a rotating shaft, for applying a force which is substantially constant in magnitude and instantaneously applicable at all times, electro-magnetic means for applying such a force to the correcting means to render it operative, and an electric circuit comprising a vessel containing mercury and an upwardly extending conducting pin above, and in close 80 proximity to, the surface of the mercury at one side, and means whereby the pin is raised from the mercury by the movement of the correcting means.

3. In a flying machine, means for correcting the level of the machine, an element, as a rotating shaft, for applying a force which is substantially constant in magnitude and instantaneously applicable at all times, electro-magnetic means for applying such a 90 force to the correcting means to render it operative, an electric circuit comprising a vessel containing mercury and an upwardly extending conducting pin above, and in close proximity to the surface of the mercury at 95 one side, and means whereby the pin is raised from the mercury by the movement of the correcting means, and the other side is adapted to be moved away from the first by the movement of the aileron, and substantially frictionless dampening means to dampen the movement of the first-named side.

4. In a flying machine, means for correcting the level of the machine, an element, as 105 a rotating shaft, for applying a force which is substantially constant in magnitude and instantaneously applicable at all times, electro-magnetic means for applying such a 110 force to the correcting means to render it operative, and an electric circuit having a break, of which one side is mercury contained in a tube, and the other side is an upwardly extending conducting pin in an 115 end of said tube, and means whereby said pin is moved away from the mercury by the movement of the correcting means.

5. In a flying machine, means for correcting the level of the machine, an element, as 120 a rotating shaft, for applying a force which is substantially constant in magnitude and instantaneously applicable at all times, electro-magnetic means for applying such a 125 force to the correcting means to render it operative, and an electric circuit having a break, of which one side is mercury contained in a tube formed with a cusp, and the other side is an upwardly extending con-

ducting pin in an end of said tube, and means whereby said pin is moved away from the mercury by the movement of the correcting means.

5 6. In a flying machine, means for correcting the level of the machine, an element, as a rotating shaft, for applying a force which is substantially constant in magnitude and instantaneously applicable at all times, electro-magnetic means for applying such a force to the correcting means to render it operative, and an electric circuit having a break, of which one side is mercury contained in a tube, and the other side is a contact for contacting with the mercury, and means whereby said contact is moved away from the mercury by the movement of the aileron, said means including a cam for regulating the rate at which the contact is moved.

7. In a flying machine, two means for correcting the level of the machine in opposite directions respectively, an element, as a rotating shaft, for applying a force which is substantially constant in magnitude and instantaneously applicable at all times, two electro-magnetic means for applying such force to the respective correcting means to render it operative, a tube raised at its ends, mercury in the tube, conductors depending in the ends of the tube into proximity with the mercury, one side of the circuit of each electro-magnetic means being connected to the mercury and the other sides being connected to the respective conductors, and a cam operable by the movement of each correcting means for moving away from the mercury the conductor which contacts therewith to close the circuit through the corresponding electro-magnetic means.

40 8. In a flying machine, two means for cor-

recting the level of the machine in opposite directions respectively, an element, as a rotating shaft, for applying a force which is substantially constant in magnitude and instantaneously applicable at all times, two electro-magnetic means for applying such force to the respective correcting means to render it operative, a tube raised at its ends, mercury in the tube, conductors depending in the ends of the tube into proximity with the mercury, a tube connecting said ends, insulating liquid in said tube, one side of the circuit of each electro-magnetic means being connected to the mercury and the other sides being connected to the respective conductors, and a cam operable by the movement of each correcting means for moving away from the mercury the conductor which contacts therewith to close the circuit through the corresponding electro-magnetic means.

9. In a flying machine, the combination of means for changing the relative levels of opposite parts of the machine, electro-magnetic means for controlling said changing means, a fan, rotated by the pressure of the traversed air, for generating the electricity to energize said electro-magnetic means, a contact pin, a vessel containing a conducting liquid with which said pin can be brought into contact by a difference in level of opposite parts of the machine, and means, actuated in unison with said changing means, for withdrawing said pin out of contact with said liquid, substantially as described.

In testimony whereof I have hereunto set my hand in the presence of two subscribing witnesses.
